PASQUALE D'ANGELO, OF NEWARK, NEW JERSEY.

PADLOCK.

No. 868,053.

Specification of Letters Patent.

Patented Aug. 13, 1907.

Application filed April 19, 1907. Serial No. 369,068.

To all whom it may concern:

Be it known that I, PASQUALE D'ANGELO, a subject of the King of Italy, residing at Newark, in the county of Essex and State of New Jersey, have invented certain new and useful Improvements in Padlocks; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to a lock that is particularly designed for a pad-lock, but is adapted for other uses, the lock being of the class that has a shackle arranged to slide into a casing to be locked therein, and to slide from the casing and then be swung to have one end clear the casing. The present lock is designed to snap shut, when the shackle is slid into the casing, but provides a means for locking the shackle by means of a key besides the automatic means, the key locked portion of the device preventing the unlocking by means of the spring actuated locking means, so that the key locked portion must be unlocked first.

The device provides a means for allowing longitudinal action of a key used in conjunction with the lock, so that the key can operate in different planes, in a particular sequence, to provide for the unlocking of different elements in their turn to complete the unlocking of the device.

30 The invention is illustrated in the accompanying drawing, in which

Figure 1 is a face view of the lock with one side thereof removed, with the lock after it is shut, showing the spring actuating means in engagement with the shackle. Fig. 2 is a similar view showing the lock completely locked. Fig. 3 is a cross-section on line 3, 3, in Fig. 2, and Fig. 4 is a horizontal section on line 4, in Fig. 1.

The device embodies a casing 10, in the top 11 of which, and in the bracket 12, is pivotally arranged the end 13 of a shackle 14. The shackle can be slid from the casing, as shown in Fig. 1 in dotted outline, and is then free to be swung around, it being rotatably arranged in the casing. The shackle has a normal tendency to emerge from the casing through the action of a spring 15 bearing on a pin 16, in the portion 13 of the shackle. The other end of the spring 15 bears on the casing.

To normally hold the shackle shut, or in its locked position, is a lever 17 pivoted at 18, and having a nose 19 to enter a slot 20 in the portion 13, the nose on the lever being forced over by the action of a spring 21 bearing on a stud 22. The end 23 of the lever 17 projects downward in close proximity to a pin 24 for the reception of a key, the relation being more specifically brought out hereafter.

When the shackle has been slid into the casing, as in Fig. 1, it is locked by the action of the spring 21 forcing the nose 19 into the slot 20. However, the lock can be securely locked by a key manipulation of some of the parts, this being done by a key 25, shown in dotted outline in Figs. 2 and 3. This key bears on a block 26 which is slid over by the action of the key, and has the stud 27 enter a perforation 28 in the end 29 of the shackle 14, the block being guided by the pin 27 passing through the bearing plate 28a and also by the rod 29 sliding in the forked support 30. This forcing of the block is done against the action of a spring 31 which bears against the block, being held against displacement by a pin 32, and the block having a flat plate 33 attached thereto which has a notch 34. When the block has passed over to the point shown in Fig. 2, and where the key 25 will now just clear it, the block is locked by the finger 35 arranged to slide in suitable bearings, and being actuated by the spring 36 to force it up into the notch 34. The finger 35 has a lug 37 thereon. The key 25, after the lock is locked, can be swung around without any hindrance when normally operated. This is due to the fact that the key has cleared the bottom of the block 26, and the lug 37 and the end 23 of the lever 17 are out of the plane of rotation of the key. The key revolves on a key-pin 24 which is narrowed down on its inner portion to form a shoulder for a stop piece for the washer 38, which is held tight by the action of a spring 39. To release the lock, the key-operated locked portion must be unlocked by means of the key, and the key 25 is forced in against the action of the spring 39 until it is within the plane of the lug 37, which will be apparent from Figs. 3 and 4. When the key is pushed in the required distance, it follows the path as indicated at a in Fig. 2, and when the lug 37 is forced downward by the key, it causes the pin 35 to release the plate 33 of the block 26, and the spring 31 operates to throw the block 26 to cause the pin 27 to be withdrawn from the end 29 of the shackle 14. The parts then assume the position shown in Fig. 1, and the key cannot be thrown back in the reversed direction on account of the lower end of the block 26 being in its path of travel. The key is thus continued in the direction of the arrow a, and when the key is twisted around to be on the left side, as we look at the drawing, of the end 23 of the lever 17, it is forced in against the action of the spring 39 much further than it was necessary to force it for the operation of the lug 37, as the end 23 of the lever is in a different plane from the lug 37, as is shown in Fig. 4.

Pressure on the lever, in the direction of the arrow b in Fig. 2, causes the nose 19 to be unlocked from the notch 20, and the spring 15 forces the shackle 14 to snap out of its casing to allow the end 28 to be swung out of alignment with the perforation by means of which it enters the casing. A guard 40 can be placed inside the casing adjacent to the washer 38 so that the key, when it

is inserted in the lock, is abruptly stopped so as to convey the impression that it cannot be further forced into the casing. The guard 40 is arranged to partly surround the pin 24, and it causes the rotation of the key 5 25 in but one plane for a part of its rotation. The spring 39 is stiff so that any accidental longitudinal movement of the key is avoided, and there is no suggestion of a yielding pressure to an ordinary user of the key.

10 It will be seen, from this description, that the key operates in three planes, first to lock the key-operated portion of the device by engaging the block 26, and must then be forced in first along its pin to engage the lug 27, and must be released to clear the guard 40 15 and then forcing in still further to engage the end 23 of the lever to unlock the spring actuated locking portion.

Having thus described my invention, what I claim is:—

1. A lock comprising a casing, a shackle to be locked 20 therein having its ends arranged to enter the casing, a spring-operated latch to lock the shackle, a key-operated locking means to engage the shackle, the spring-operated locking means and the key-operated locking means being arranged in different planes, in combination with a releasing means adapted to successively operate in the different planes.

2. A lock comprising a casing, a shackle to be locked 30 therein having its ends arranged to enter the casing, a spring-operated latch to lock the shackle, a key-operated locking means to engage the shackle, the spring-operated locking means and the key-operated locking means being arranged in different planes, in combination with a key for entering the casing and adapted to rotate in the different planes.

3. A lock comprising a casing, a shackle to be locked 35 therein having its ends arranged to enter the casing, a spring-operated latch to lock the shackle, a key-operated locking means to engage the shackle, the spring-operated locking means and the key-operated locking means being arranged in different planes, in combination with a key for entering the casing and adapted to rotate in the different planes, and a stop for limiting the movement of the key to one plane during a portion of its rotation.

4. A lock comprising a casing, a shackle arranged there- 40 in, a spring-operated latch to lock the shackle, a key-operated locking means, a finger to lock the key-operated means, the latch, the key-operated means, and the finger being arranged in different planes, in combination with a key to be operated in the different planes.

5. A lock comprising a casing, a shackle to be locked 45 in the casing, a spring-operated lever to engage the shackle to lock it, a key-operated locking means, a finger to engage the key-operated means in its locked position to secure it there, the spring-operated lever, the key-operated means, and the finger all lying in different planes, in combination with a key adapted to be rotated in the different planes, a stop to limit the key at a portion of its rotation, and a spring arranged to normally hold the key 55 beyond the stop.

6. A lock comprising a casing, a shackle to be locked 60

in the casing, a spring-operated lever to engage the shackle to lock it, a key-operated locking means, a finger to engage the key-operated means in its locked position to secure it there, the spring-operated lever, the key-operated means, and the finger all lying in different planes, a pin 65 for the reception of a key, a washer on the pin, means to limit its movement, a spring bearing on the washer, in combination with a key adapted to envelop the pin and rotate thereon in the different planes, and a stop piece in line with the washer and adapted to limit the movement 70 of the key during a portion of its rotation.

7. A lock comprising a casing, a shackle, a spring to normally eject the shackle, a spring-operated locking means to engage the shackle, a key-operated means to lock the shackle, a finger to fasten the last mentioned 75 means in its locked position, a spring to normally hold the key-operated means unlocked, the spring-operated locking means, the key-operated locking mechanism, and the finger each lying in a different plane, in combination with a key adapted to operate in the different planes to 80 engage the finger and the spring-operated means.

8. A lock comprising a casing, a shackle to enter the casing, a spring engaging one end of the shackle acting to eject the shackle from the casing, the shackle in its ejected position being rotatable on the casing, one end of 85 the shackle being shorter than the other, a spring-operated locking lever to engage the long end of the shackle, a block having a stud to enter the short end of the shackle, a spring to normally operate the block to unlock the stud, the block being adapted to be key-operated to be locked, 90 the block having a notch therein, a finger adapted to be placed in register with the notch when the block is in its locked position, a spring to normally throw the finger in engagement with the block, a lug on the finger for its key-operation, the spring-operated locking lever, the block, 95 and the lug being placed in different planes, in combination with a key adapted to rotate in the casing in the different planes.

9. A lock comprising a casing, a shackle to enter the casing, a spring engaging one end of the shackle acting 100 to eject the shackle from the casing, the shackle in its ejected position being rotatable on the casing, one end of the shackle being shorter than the other, a spring-operated locking lever to engage the long end of the shackle, a block having a stud to enter the short end of the shackle, 105 a spring to normally operate the block to unlock the stud, the block being adapted to be key-operated to be locked, the block having a notch therein, a finger adapted to be placed in register with the notch when the block is in its locked position, a spring to normally throw the finger in engagement with the block, a lug on the finger for its key-operation, the spring-operated locking lever, the block, and the lug being placed in different planes, in combination 110 with a key adapted to rotate in the casing in the different planes, and a spring adapted to abut on the key and normally hold it out of the plane of the lug and the spring-operated lever.

In testimony, that I claim the foregoing, I have hereunto set my hand this 18th day of April 1907.

PASQUALE D'ANGELO.
